CLAIM

The ornamental design for an open ended industrial pipe cap, as shown and described.

DESCRIPTION

FIG. 1 is a perspective view of a first embodiment of an open ended industrial pipe cap showing my new design;

FIG. 2 is a top view thereof;

FIG. 3 is a side view thereof; with the opposite side view being thereto;

FIG. 4 is a side view thereof, rotated 90 degrees away from the side shown in FIG. 3;

FIG. 5 is an opposite side view thereof;

FIG. 6 is a bottom view thereof;

FIG. 7 is a perspective view of a second embodiment of an open ended industrial pipe cap showing my new design;

FIG. 8 is a top view thereof;

FIG. 9 is a side view thereof; with the opposite side view being thereto;

FIG. 10 is a side view thereof, rotated 90 degrees away from the side shown in FIG. 9;

FIG. 11 is an opposite side view thereof; and,

FIG. 12 is a bottom view thereof.
